Meyers, Cushman & Ree

UNITED STATES PATENT OFFICE.

WALTER J. McDONNELL, OF MATTOON, ILLINOIS.

ELECTRIC SEMAPHORE SIGNAL.

Application filed July 29, 1918. Serial No. 247,173.

To all whom it may concern:

Be it known that I, WALTER J. McDONNELL, a citizen of the United States, residing at Mattoon, in the county of Coles and State of Illinois, have invented new and useful Improvements in Electric Semaphore Signals, of which the following is a specification.

This invention relates to certain novel and useful improvements in signaling apparatus, and has particular application to electrically operated signals of the semaphore type.

As is well known, for military, naval, field, and other purposes, it is the practice to transmit messages through the agency of signal flags, lanterns or other suitable instrumentalities, the message being spelled out or defined by resorting to the use of a regular or determined code of signals, the position in which the signaling instrumentality, or instrumentalities is held, indicating a selected letter, number, word or phrase as the case may be. Usually the signaling instrumentalities are manually operated, and as the person signaling must necessarily occupy a more or less exposed position in order that his signaling instrumentalities, whether flag or lantern, may be seen by the observer to whom he is sending the message, the danger and risk of being wounded or killed during battle, or on an active fighting front, is obvious.

One of the purposes of my invention therefore is the provision of a signaling apparatus, preferably of the semaphore type, wherein the signaling instrumentalities may be exposed to the view of the observer or receiver, while the operator or sender may occupy a position of concealment and comparative safety, as within the shelter of a trench, dugout or other place.

Another object of my invention is the provision of a signaling apparatus of this type wherein the signaling instrumentalities, either flag or lantern, are electrically controlled and operated, so that not only may the messages be sent with greater speed and accuracy than when the signaling instrumentalities are manually operated, but the muscular strain and consequent physical

weariness incident to long continued signaling by hand is avoided.

It is also my purpose to provide an electric semaphore signaling apparatus which may be readily and speedily assembled and dismantled, and which may be operated from a remote or distant station or point.

I also aim to provide a signaling apparatus which will embody the desired features of simplicity, efficiency and reliability, which is of light construction and may be packed within a small compass and readily transported from place to place and which may be manufactured and marketed at a relatively low cost.

With the above recited objects and others of a similar nature in view, my invention consists in the construction, combination and arrangement of parts set forth in and falling within the scope of the appended claims.

In the accompanying drawings:

Fig. 1 is a perspective view of an assembled apparatus embodying my invention and showing the use of semaphore flag arms.

Fig. 2 is a top plan view of the solenoid casing with the attached or pivoted flag arms.

Fig. 3 is a vertical sectional view taken through the casing.

Fig. 4 is a longitudinal sectional view taken through a portion of the casing and showing the enclosed solenoids and the rack and pinion operating mechanism of one of the flag arms.

Fig. 5 is a plan view of one of the junction plates for the solenoid wires.

Fig. 6 is a plan view of the controller.

Fig. 7 is a vertical sectional view taken through the controller.

Fig. 8 is a diagrammatic illustration of the wiring of my signal.

Fig. 9 is a top plan view of a modified form of semaphore showing the flag arms provided with lamps.

Referring now to the accompanying drawings in detail, and particularly to Fig. 1, the letter A indicates a suitable, collapsible supporting base, in the present instance of tripod form and carrying the collars 1 for holding the lower end of the removable,

tubular standard 2 in which telescopes the tubular, removable post 3, which may be fastened adjustably by means of the set screw 4, as will be readily understood. At 5 the upper end of the post 3 is removably mounted the casing B. This casing, which may be of any desired shape or form and made of any suitable material, may be secured to the post 3 by screwing the threaded 10 nipple 5 on to the threaded end 6 of the post, the nipple being attached to the bottom of the casing by means of the clamp 7 which is screwed as at 8 to the bottom of the casing. The central portion of the bottom 15 wall of the casing is cut out to receive the junction plate 9 of insulating material, this junction plate 9 being superposed upon and in contact with a similar insulated junction plate 10, which rests in the dished head 11 20 held to the casing by the clamp 7 and from which dished head the nipple 5 depends. The purpose of these junction plates will be hereafter apparent.

Within the casing are positioned two 25 solenoids S and T, which are similar in construction and operation, the solenoid S being employed in the operation of the flag arm C, while the solenoid T is for the flag arm D. Each solenoid consists, in the present instance, of eight coils 12 of standard magnet wire, the size and number of turns being determined by the voltage adopted. The coils are insulated from each other by mica washers 13 and are mounted upon brass tubing 14. Each solenoid is provided with a sliding core or plunger 15, the outer end of which terminates in a rack bar 16 working in roller bearings 17 mounted near the end of the casing. The teeth of each rack bar 40 engage with a gear pinion 18 mounted on the shaft 19 journaled transversely of the casing, one end of the shaft projecting through the adjacent side wall of the casing and having adjustably fastened thereon by 45 means of the set screw 20, a socket 21 which carries the flag arm. Thus the flag arm may be removed from its shaft 19 when the apparatus is being dismantled. Projecting from each end of the casing is a sleeve 22 50 which forms a housing for the outer portion of the adjacent rack bar.

The controller is indicated as an entirety by the letter E and embodies a suitable box in which the electric battery is disposed, the battery being indicated diagrammatically and conventionally at X in Fig. 8. Mounted upon the battery box is the controller box F, the top of which has imposed thereon the indicator dial 23 containing the characters, such as letters and numbers and words, making up the signal code, or used in the formation of the message. Concentric with and surrounded by the indicator dial is a circular rack 24 over which moves the indicator handle or pointer 25 mounted to turn

with the shaft 26, which extends through the sleeve 27 located interiorly of the box. This indicator dial carries the usual spring pressed pin 28 socketed in the knob 29, the pin being adapted to engage with and be held by the teeth of the rack 24, the handle being provided with the usual arrow head pointer 30. The lower end of the shaft 26 is fastened with and carries a block 31 of insulated material, this block of course turning with the rotation of the shaft. To the under-side of this block is fastened a contact ring 32 against which bears the spring contact arm 33. This spring contact arm 33, which forms a terminal of the positive feed wire 34 leading from the battery, is connected as at 35 to an insulation ring 36 which surrounds the block 31 and carries an outer ring of contact plates 37 and an inner ring of contact plates 38, the outer ring of the contact plates being connected with the coils of the solenoid, controlling the left hand flag arm C, while the plates of the inner ring 38 are connected with the coils of the solenoid T controlling the right hand flag arm D. It will be noted by reference to the diagrammatic view of Fig. 8, that the two rings of the contact plates each bear numbers from 1 to 8, thus corresponding to the eight coils of each solenoid, and that each numbered plate is connected through a conductor 39 with a correspondingly numbered coil of its solenoid, and it will be further noted that as there are more than eight plates to a ring, certain numbered plates being duplicated. For instance, in the outer ring, we find the No. 2 appears on four plates, but in each instance, these plates are all connected to the No. 2 coils of the solenoid, likewise on the inner ring of plates, we find the No. 3 repeated four times, but these No. 3 plates are all connected with the No. 3 coils of the solenoids. The rings of the contact plates are arranged to correspond with the code indicated on the dial of Fig. 6.

The block 31 turning with the shaft 26, carries a pair of contact brushes 40 and 41, adapted to bear against the contact plates of the outer and inner rings 37 and 38 respectively, these contact brushes of course being connected with the plate 32 through conducting screws 42. When the handle or pointer is turned, for instance, to the position shown in Figs. 6 and 7, to move the two flag arms of the solenoid to indicate the position of code character C³, the brushes 40 and 41 will rest upon the two contact plates of the rings 37 and 38 which will lie in radial alignment with and directly below the character C³, and form a part of the circuit of this code sign C³. The current passing from the battery X through the switch Y, closed at that time, will pass along through the feed conductor 34 to the

spring contact arm 33, ring 32 and screws 42 to the contact brushes 40 and 41, and thence through the two respective and proper conductors 39 leading to the corresponding coils of the solenoid. The two coils are thus energized, and the current passes through these coils to the return conductors 43 of the coils, and which return conductors are connected with a common return wire 44 connected to the central contact pin 45, carried by the plate 9, which pin 45 movably contacts with the contact socket 46 to which is connected the common return cable 44', forming a continuation of the return cable 44, this cable 44' leading back to the battery. The various conductor wires extending between the controller and the semaphore casing B, are made up into a multiple-strand, properly insulated cable 47, which lead up through the hollow posts supporting the casing B, the feed conductors branching off in the dished head 11 fastened to the bottom of the casing, as shown at 48, and are connected to their respective contact sockets 49, which seat contact screws or pins 50, and to which are connected the sections of the feed conductor wires leading to the coils. I employ the two plates 9 and 10 with the removably-associated contact members, so that in the packing or dismantling of the apparatus, the casing B with its solenoid coils, may be separated from the conductor cable 47, and the casing may be removed from the hollow post section 3 by loosening the latch 51 and sliding the plate 11 sidewise out of the clamp 7 as will be readily understood by reference to Fig. 1.

I have briefly described one arrangement of the electric wiring for energizing the solenoids, but it will be understood that the wiring arrangement may be varied to suit the particular apparatus, or the particular conditions under which it is to be worked. It will be apparent, that when the handle or pointer 25 is swung to a desired position, for instance, so as to indicate C^s as shown in Fig. 6, one coil of the solenoid S and one coil of the solenoid T will be energized, and the cores or plungers of the solenoid will be shifted a predetermined distance, and this shifting of the cores or plungers will cause the turning of the gear wheels 18, by the rack sections 16 of the plunger, of course, thus moving the flag arms C and D to the desired position to indicate the particular word or letter of the code symbolized by the character C^s. In brief, the pointer hand may be swung over the dial to any selected code symbol and the flag arms C and D will be moved to such a position as to indicate to the observer such code symbol.

In Fig. 9 I have shown a slightly modified arrangement of the invention which may be used at night, or where it is desired to signal by means of a lamp, and in this in-

stance, the flag arms C' and D' are provided with electric lamps v and w respectively, suitably connected or electrically wired as at v' and w' to the electric circuit of the apparatus. An electric lamp Z is located at the center of the casing, or between the arms, and is also wired into the electric circuit, but this lamp of course is stationary and simply acts as a guide or indicator. The lamps of the arms and the central lamp may be wired in any ordinary and well-known manner.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. A semaphore signaling apparatus for transmitting messages by selected combinations of positions of semaphore arms, comprising a casing, two oppositely directed semaphore arms pivotally carried by the casing at opposite ends thereof, the said arms occupying right and left-hand positions respectively, each of said arms being movable selectively into any of more than two signal indicating positions, electrical means for operating the semaphore arms, and a manually operable controlling means for controlling the said electrical means to produce a variety of combinations of signal indications of said arms for the transmission of messages.

2. In a signaling apparatus of the class described, the combination with a casing, of a semaphore arm pivotally connected therewith, a rack and gear mechanism connected with said arm, a multiple step solenoid associated with the rack and gear mechanism and adapted to actuate the latter, and electrical means for selectively energizing a predetermined portion of the solenoid to position said arm in any one of more than two predetermined positions, including a controller and electrical connections between the controller and the solenoid.

3. In a signaling apparatus, two sets of axially aligned solenoids, armatures longitudinally movable in each set, a shiftable signaling instrumentality connected with each armature, and a controlling means adapted to position both instrumentalities simultaneously in any one of more than two predetermined positions by selective operation of solenoids of both sides.

4. A semaphore signaling apparatus for transmitting messages by selected combinations of positions of semaphore arms, comprising a casing carrying a pair of sema-

phore arms, each movable selectively into any of more than two signal indicating positions, two sets of axially aligned solenoids in said casing, one for each signaling arm, 5 an armature connected to a signaling arm longitudinally movable in each solenoid set, and a controlling means for energizing the

said solenoids to produce a variety of combinations of signal indications of said arms for the transmission of messages.

10 In testimony whereof I have heremunto set my hand.

WALTER J. McDONNELL.
